UNITED STATES PATENT OFFICE

FRED B. HAYES, OF FORT WAYNE, INDIANA, ASSIGNOR TO THE GAS MACHINERY COMPANY, OF CLEVELAND, OHIO, A CORPORATION OF OHIO

FUEL CHARGER FOR GAS GENERATORS

Application filed July 17, 1929. Serial No. 378,875.

This invention relates to mechanical fuel charging devices for use in charging gas generators with coal or coke, without interfering with the operation of the gas set.

5 One object of the invention is to so construct the charger that the fuel receiving opening of the generator nozzle normally will be sealed and will be opened automatically when the generator is to be charged 10 with fuel.

Another object is to produce means for automatically spreading the fuel being charged into the generator to insure proper distribution of the fuel over the fire bed.

15 Another object is to provide a movable fuel container connected with the charger and operatively connected with the fuel spreading and generator sealing means, whereby the proper co-ordinated actuation 20 of said parts is insured. The movable fuel container has an opening for the reception of fuel from a conveyor, and closure means for said opening. The closure means are also operatively connected with the generator 25 sealing means so that said container door will be closed before the generator sealing means is opened and the fuel container is moved to charging position. Thus, while the fuel container is movable relative to the charger body, it is an integral part thereof, and generator pressure is maintained even during 30 the charging period.

The design of the fuel hopper and nozzles leading from the hopper to the body of the 35 charger is such that stoppage of coal or coke is prevented. The movable hopper and nozzles render it practical to use a low type conveyor for carrying the fuel to the hopper.

40 The means for spreading the fuel as it enters the generator, also acting as a seal for the generator opening, is operatively connected with the fuel container, and the latter acts as a counterbalance for the spreader, and insures the return of the spreader to 45 its sealing position when the generator is not being charged with fuel. This is of great advantage because should the hydraulic pressure or other means for operating the spreader fail, the spreader will be returned 50 to its closed or tight position by the weight

of the hopper. Thereby the spreader is saved from damage which would result if it were allowed to remain in its lowered position over the fuel bed during the blasting or further operation of the generator. The operator may readily determine the position of the spreader or sealing disc by the position of the hopper. 55

The spreader is so connected with the hopper or fuel container that the spreader is well 60 lowered into the generator before the fuel begins to be discharged from the hopper.

Another advantage grows out of the provision of operative connections between the spreader actuating mechanism and the mechanism for actuating the hopper door, which 65 prevents the spreader disc being lowered before the hopper door is closed.

In the drawings:—

Figure 1 is a vertical sectional view of an 70 automatic fuel charger embodying my invention, the parts being shown in loading position.

Figure 2 is a view similar to Figure 1, but showing the parts in charging position. 75

Figure 3 is a plan view of the construction shown in Figure 1.

Figure 4 is a horizontal sectional view taken on the line 4—4 of Figure 1, looking downwardly as indicated by the arrows. 80

Figure 5 is a vertical sectional view taken on the line 5—5 of Figure 2.

In that embodiment of my invention shown in the drawings, 5 indicates a track on any suitable support or floor which is substantially on a level with the top of generator charging nozzle A. 6 is a truck or carriage having wheels 7, journalled therein for traveling over track 5. The body 8 of the fuel charger is mounted on the truck 6 and it is capable of being raised and lowered relative to said carriage to permit it to be positioned over and removed from the charging opening of the generator nozzle A. Said body is shown as substantially cylindrical in 85 cross section and tapering at 8' toward an opening adapted to fit over the opening in the top of the generator nozzle A. 90

At opposite sides the charger body 8 is provided with horizontally disposed tubular ex- 100

tensions 9, in each of which is mounted one end of the rotatable nozzles 10 leading from the hopper 11 to the charger body 8. The inner surfaces of each of the tubular extensions 9 are provided with an annular shoulder 12 for the end of the nozzle 10 to bear against and packing 13 between the extension member 9 and nozzle 10 to form a pressure tight fit between said parts while permitting rotation of the nozzles in said tubular extension members 9.

That part of the wall of the nozzle 10 which forms the side toward the left in Figures 3 and 4, when the hopper is in loading position, and which forms the lower or fuel supporting wall portion when the hopper has been raised to charging position, as shown in Figure 2, extends at approximately a 45° angle to a horizontal plane. A semi-circumferential lip 10' is formed on the end of the nozzle 10, adjacent said inclined wall of the nozzle, for the purpose of providing a concentric bearing surface on the nozzle 10 for co-operation with the tubular extension 9 on the charger body 8. Said inclined portion of the nozzle wall has been designated as 10a and its form is such that when the hopper 11 is in raised position, fuel will slide easily over the inner surface of the hopper and nozzle, downwardly and inwardly toward the charger body 8 and thence into the generator nozzle A.

When the hopper 11 is in raised or charging position, the surface at the lower end of the nozzle, indicated at 10b, will be in alignment with the tapered surface 8' of the charger body. This is best shown in Figure 5 from which it will be seen that fuel will slide downwardly and inwardly over a smooth unobstructed surface into the generator nozzle A.

The fuel hopper 11 which is rigidly secured to one end of each of said nozzles 10 has a division plate 14 extending upwardly from its bottom wall 15 to a height indicated by the line 16 in Figure 1. This division plate 14 divides the hopper 11 into two passage ways, each communicating with a nozzle 10, and insures the equal distribution of the fuel as it is being loaded into the hopper.

Centrally located in the top wall of the hopper 11, that is, at the junction of the legs of the hopper and above the division plate 14, is a circular opening 17 adapted to be closed by the sliding door 18. The door 18 is actuated by the hydraulic cylinder 19 and rack 20 meshing with the pinion 21 operatively connected with the rack and pinion 22 on the door 18.

The charger body 8 is firmly held down on the generator nozzle A, when the carriage is in position, by clamps 23, three being usually employed.

A fuel spreader comprising a shaft 24 and a spreader disc 25 is mounted in the charger. The top wall of the charger body 8 has a

depending sleeve 26, integral therewith, forming a bearing in which the spreader shaft 24 is slidably mounted. Packing and lubricating means 27 are provided. The spreader shaft 24 is actuated by an hydraulic operating cylinder 28 in which the piston 29 connected to the top of the shaft 24 is slidably mounted. The cylinder 28 is supported by a suitable frame 28' extending rigidly from the charger body 8.

About midway between its ends, at a point just below the hydraulic cylinder 28 when the shaft 24 is in its raised position, there is rigidly attached to said shaft 24 a two-arm bracket 30. The arms of this bracket 30 extend horizontally and radially from the shaft 24 toward the hopper 11. To each arm of the bracket 30 is secured one end of a steel cable 31, looped over a pulley 32 which is loosely mounted on a shaft supported by a bracket 33, located above the bracket 30 and rigidly secured to the frame 28', or other suitable support. The cable 31 extends downwardly from the pulley 32 to another pulley 34 on the frame and then extends downwardly to where its end is firmly secured to the hopper 11, as indicated at 35. A turn buckle 36 is provided in the cable for adjusting the cable to keep it taut and to properly co-ordinate the hopper movement and spreader actuation.

37 indicates a sight cock, 38 an inspection door, 39 a hand wheel for operating the mechanism for raising and lowering the charger body relative to the carriage. 40 is a spring secured to the carriage and to the bottom of the hopper for facilitating the return movement of the hopper. 41 is a landing lug or support for receiving the hopper when the operating mechanism is released for any reason.

A fuel conveyor belt is indicated at 42, and a conveyor chute at 43, the latter being pivotally mounted on a shaft 44 on which is also mounted a lever 45 having a counterweight 46 on one of its arms. An arm 47 on the hopper 11 alternately contacts with the chute 43 and the lever 45 for lowering and raising the chute. Thus the chute is raised by the hopper arm 47 and the way is cleared for the hopper to assume charging position.

The operation of the device is as follows:—

The hydraulic cylinder 28 is operatively connected with the control mechanism of a conventional blue gas or water gas set. Normally the spreader shaft 24 is in its raised position as shown in Figure 1 so that the spreader disc 25 is seated in the opening in the tapered portion 8' of the charger body 8, thereby sealing the generator nozzle opening. The hopper 11 and nozzles 10 are also in their lowered position and in this position the door 18 for the hopper opening 17 may be opened. This is accomplished automatically by operative connections between the hy-

draulic cylinder 19 and the control mechanism of the set, or by operative connections between the hydraulic cylinders 19 and 28. The fuel may be loaded into the hopper 11 by the conveyor 42 and chute 43 the latter being in its lowered position as shown in Figure 1. The fuel being loaded into the hopper will be divided by the plate 14 and will be ready to slide downwardly through each leg of the hopper to the nozzles 10.

At a predetermined time the hydraulic mechanism will actuate the spreader shaft 24, whereby the spreader disc 25 will be lowered, the ends of the cables 31 attached to the bracket 30 will be drawn downwardly with the shaft 24, thereby raising the hopper 11; but first the hopper door 18 will have been closed so that pressure within the generator will be maintained during the charging period. The raising of the hopper 11 causes the nozzle 10 to have rotative movement in the tubular extension members 9 of the charger body 8 and bring the inclined walls 10a toward the bottom, and the fuel will slide freely downwardly and inwardly through the nozzles, and through the charger body to the curved upper surface of the spreader 25 by which it is distributed over the fuel bed.

When the charging operation has been completed the spreader will be automatically raised by the hydraulic operating cylinder 28 which is operatively connected to the control mechanism of the gas set and the hopper and nozzles will be lowered. The hopper acts as a counterbalance for facilitating the return movement and insures the sealing of the generator opening before the hopper door may again be open for reloading the hopper.

Even if the hydraulic pressure in the cylinder 28 should fail, the weight of the hopper, by assuming its lowered position and through its operative connections with the spreader would insure retaining the spreader shaft in its raised position and consequent sealing of the generator opening by the disc 25. The position of the hopper readily indicates to the operator the position of the disc 25.

Instead of using a hopper 11 having two legs and two nozzles, each rotatably mounted in a tubular extension 9, it is feasible to use a single hopper, the nozzle of which may be movably mounted in the charger body 8 so as to be capable of being raised and lowered by the same kind of mechanism used in connection with the twin nozzles. In this connection, it will also be understood that the operative connection between the hopper and spreader shaft 24 may comprise any suitable gearing which may be substituted for the cable connections or for the hydraulic operating cylinder and cable connections.

In some of the appended claims, the words "fuel container" have been used to indicate the parts herein described as a hopper and nozzles, and it will be understood that said phrase, "fuel container", is intended to cover either the single or double type hopper and nozzles.

Obviously, changes may be made in details of construction without departing from the scope of my invention, and I do not intend to be limited to the exact form shown and described, except as pointed out in the appended claims.

I claim:

1. A mechanical fuel charger comprising a charger body having an opening therein to register with the fuel receiving opening of a generator, a fuel container movably mounted in the charger body and in continuous communication with the interior thereof, hopper-closure means for the fuel container, closure means for the opening in the charger body, means for actuating the closure means for the charger opening, and operative connections between the movable fuel container and said closure means for the charger opening.

2. A mechanical fuel charger comprising a charger body having an opening therein to register with the fuel receiving opening of a generator, a fuel container movably mounted in the charger body and in communication with the interior thereof, closure means for the fuel container, closure means for the opening in the charger body, means for actuating the closure means for the charger opening, and operative connections between the movable fuel container and said closure means for the charger opening, whereby said charger body opening is sealed when the movable fuel container is in non-charging position, said closure means for the charger comprising a disc adapted to seat in said opening, and a shaft extending upwardly from the disc, and said operative connections between the fuel container and said closure means including a cable connected to the fuel container and the shaft.

3. A mechanical fuel charger comprising a charger body having an opening therein to register with the fuel receiving opening of a generator, a fuel container movably mounted in the charger body and in communication with the interior thereof, movable closure means for the fuel container, closure means for the opening in the charger body, means for actuating the closure means for the charger opening, said fuel container comprising a hopper having two legs, each extending toward opposite sides of the charger body, and a curved nozzle secured to each hopper leg for connecting it to said body.

4. A mechanical fuel charger comprising a charger body having an opening therein

to register with the fuel receiving opening of a generator, a fuel container movably mounted in the charger body and in communication with the interior thereof, movable closure means for the fuel container, closure means for the opening in the charger body, means for actuating the closure means for the charger opening, operative connections between the movable fuel container and said closure means for the charger opening, and means for actuating the closure means for the fuel container, said closure means for the fuel container and said closure means for the charger body opening being connected in cooperative relation to permit the opening of the former only when the latter are closed.

5. A mechanical fuel charger comprising a charger body having an opening therein to register with the fuel receiving opening of a generator, a fuel container movably mounted in the charger body and in communication with the interior thereof, movable closure means for the fuel container, closure means for the opening in the charger body, and means for actuating the closure means for the charger opening, said fuel container comprising a fuel receiving hopper having an inclined nozzle formed with an 10 inwardly extending journal, and the charger being formed with a bearing within which the charger nozzle journal is mounted.

6. A mechanical fuel charger comprising a charger body having an opening therein to register with the fuel receiving opening of a generator, a fuel container movably mounted in the charger body and in communication with the interior thereof, closure means for the fuel container, closure means for the opening in the charger body, means for actuating the closure means for the charger opening, and operative connections between the movable fuel container and said closure means for the charger opening, said 15 fuel container comprising a hopper having two legs, each extending toward opposite sides of the charger body, and a curved nozzle secured to each hopper leg for connecting it to said body, and the charger body having a pair of tubular extensions on opposite sides thereof to receive said nozzles.

In testimony, that I claim the foregoing as my invention, I affix my signature, this 20 9th day of July, 1929.

55 FRED B. HAYES.
